UNITED STATES PATENT OFFICE.

JACOB MILLER, OF WEST FALLS, NEW YORK.

DESIGN FOR A CLOTHESLINE-CLAMP.

55,953.

Specification for Design.

Patented Aug. 3, 1920.

Application filed February 9, 1920. Serial No. 357,364. Term of patent 14 years.

To all whom it may concern:

Be it known that I, JACOB MILLER, a citizen of the United States, residing at West Falls, in the county of Erie and State of New York, have invented a new, original, and ornamental Design for a Clothesline-Clamp, of which the following is a specification, reference being had to the accompanying drawings, forming part thereof.

Figure 1 is an edge view of a clothesline clamp showing my new design. Fig. 2 is a side view of the same.

I claim:

The ornamental design for a clothesline clamp, as shown.

JACOB MILLER.
